ARTHUR ROEDER
INVENTOR

BY *Victor J. Evans*

ATTORNEY

UNITED STATES PATENT OFFICE.

ARTHUR ROEDER, OF BENTON HARBOR, MICHIGAN.

AIR COOLER FOR MOTORS.

Application filed April 5, 1924. Serial No. 704,547.

To all whom it may concern:

Be it known that I, ARTHUR ROEDER, a citizen of the United States, residing at Benton Harbor, in the county of Berrien, and State of Michigan, have invented new and useful Improvements in Air Coolers for Motors, of which the following is a specification.

This invention relates to a cooling system for internal combustion engines and has for its primary object the construction of an air cooler which will effectively cool a motor by air.

An object of the invention is the simple substantial manner in which the parts are constructed so that the required volume of air may be caused to circulate around the motor.

Besides the above my invention is distinguished in the combination of an air cooling system with means for controlling the amount of air passing so as to control the cooling action.

With these and other objects in view the invention will be better understood from the following detailed description taken in connection with the accompanying drawing wherein:

Fig. 1 is a diagrammatic view showing the application of my invention.

Fig. 2 is a sectional view on the line 2—2 of Fig. 1.

Fig. 3 is a cross sectional view.

Fig. 4 is a detailed view of the shutter construction.

Again referring to the drawing illustrating one of the many constructions of my invention the numeral 1 designates a frame which may be constructed to imitate the usual radiator now in use. This frame 1 forms an air opening 2 that is controlled by a plurality of shutters 3 operated by the

link mechanism 4 which in turn is controlled by the adjuster 5 on the dashboard 6. The rear of the opening 2 is closed by a collector 7 which communicates with a fan casing 8 through the outlet 9. This fan casing 8 communicates with a conduit 10 which in turn communicates with the motor jacket 11. A fan 12, arranged in the fan casing, has a gear drive 13 with the shaft 14 driven by the motor.

From the foregoing description taken in connection with the accompanying drawing it will be apparent that my construction is such that the required volume of air can be forced through the motor to cool same and this cooling action is such that the motor may be run and most efficiently tempered by the manual manipulation of the shutters.

It is, of course, to be understood that the invention may be constructed in various other manners and the parts associated in different relations, therefore, I do not desire to be limited in any manner except as set forth in the claim hereunto appended.

Having thus described my invention what I claim is:

An air cooler for motors comprising a frame forming an air opening, a plurality of shutters controlling the passage of air through said opening, link mechanism for operating said shutters, a collector formed at the rear of said opening, said collector having an outlet, a fan casing in communication with the collector through the outlet, a fan within the casing driven from the motor and a conduit forming communication between the casing and the motor jacket.

In testimony whereof I affix my signature.

ARTHUR ROEDER.
